CLAIM

The ornamental design for a clip, as shown and described.

DESCRIPTION

FIG. 1 is a perspective view of a clip showing a new design; FIG. 2 is a front elevation view thereof, the rear view being a mirror image thereof;

FIG. 3 is a left side elevation view thereof, the right side being a mirror image thereof;

FIG. 4 is a top plan view thereof;

FIG. 5 is a bottom plan view thereof;

FIG. 6 is a top front perspective view of the clip of FIG. 1 shown in an installed configuration; and,

FIG. 7 is a bottom rear perspective view of the clip of FIG. 1 shown in an installed configuration.

In the drawings the dash-dash broken lines are for the purpose of illustrating environment only and form no part of the claimed design.
